Attorney

UNITED STATES PATENT OFFICE.

LAURENCE HUSTON KIRK, OF HAVRE DE GRACE, MARYLAND, ASSIGNOR TO MARYLAND METAL CROSS TIE COMPANY, OF BALTIMORE, MARYLAND, A CORPORATION OF DELAWARE. METALLIC RAILWAY-TIE AND FASTENING.

1,182,772.

Specification of Letters Patent. Patented May 9, 1916.

Application filed March 17, 1916. Serial No. 84,892.

To all whom it may concern:

Be it known that I, LAURENCE H. KIRK, citizen of the United States, residing at Havre de Grace, in the county of Harford and State of Maryland, have invented certain new and useful Improvements in Metallic Railway-Ties and Fastenings, of which the following is a specification.

My invention relates to an improved means for fastening one part to another; primarily the invention relates to a metallic railway tie and rail fastening and the invention consists, essentially, of a railway-tie formed of a single piece of metal having on the upper surface near the ends, suitable seats for the rails, said tie being, also, formed below the sides of each rail seat with a pair of vertically disposed spike-receiving recesses or core-holes, which at opposite ends have their walls straight and parallel for a substantial distance and thence are connected by an intermediate portion whose walls are given a spiral formation, said recesses or core-holes being designed for the reception of the spikes which secure the rails to the tie or other part.

My invention further consists of the parts, and the constructions, arrangements and combinations of parts which I will hereinafter describe and claim.

In the accompanying drawing forming part of this specification and in which similar reference characters indicate like parts in the several views; Figure 1 is a perspective view of a railway tie as one embodiment of my invention, showing sections of the rails thereon. Fig. 2 is an enlarged longitudinal sectional view on the line 2—2 of Fig. 1, showing a spike secured in position.

While the present invention may be used wherever it is desired to securely fasten one part to another by means of a spike, or bolt, I have, for present purposes, illustrated the present improvement in connection with a metallic railway tie and fastening, which is not essentially unlike the tie disclosed in Patent No. 1,115,167, dated October 27, 1914, and which tie consists of a base flange, *a*, of suitable width and a flange, *b*, which when the tie is in position, extends perpendicularly to the base flange and rises from the center thereof and extends from end to end of the base flange, said perpendicular flange being, for the sake

of lightness and at the same time strength relative to material, formed with openings, *c*, substantially as in the aforesaid prior patent.

The tie has the usual or any desired rail-seats, *e*, which may be formed by widening the vertical flange transversely at the top to form the lateral flanges, *d*—*d* which extend for a suitable distance along the sides of the vertical flange and thus form broad and substantial seats for the base flanges of the usual railway rails, *B*, said seats having at the outer sides the upstanding shoulders, *f*, formed rigid with the vertical flange and against which shoulders abut the outer edges of the horizontal base flanges of the rails, said shoulders serving as a means for preventing lateral or outward spreading of the rails. If desired, and in fact it is so preferred, the central portions of the rail-seats, *e*, may be formed with openings, *g*, and the vertical flange of the tie beneath said seats may be formed with openings, *h*, but this is optional.

The foregoing features form no essential part of my present invention and hence I do not broadly claim the same, as it is apparent that the improvement which I am about to describe may be used with other and different forms of railway ties and as a fastening means, not only between a tie and a rail, but between any two parts which it is desired to rigidly secure one to the other, by means of a spike or bolt.

In the aforesaid prior patent, suitable vertical boxes are located at opposite sides of and vertically below each rail-seat, each of said boxes forming a spike-receiving recess longitudinally of serpentine form, in which the ordinary and substantially straight railway spike is designed to be driven and to be distorted during the driving operation, whereby the spike is made to substantially conform longitudinally to the wavy outline of the walls of the recess against which the spike is forced as it is driven into place. In the present instance, however, it is desired to give to the spike, or to an equivalent bolt, a spiral-twist rather than a longitudinal wavy form and to this end, I form the spike receiving recesses or core-holes as follows: At each end of the recess or core-hole, the walls of the same are parallel and straight, as at 2—2', for a substantial distance inward, the recess or opening being, 110

we will say, square or rectangular in cross section, but the intermediate portion which connects with said ends, has its walls in the shape of a spiral, 3, the construction being such that the straight or untwisted portions at the top and bottom of the recess or hole overcome the tendency of an inserted spike or bolt to twist out of place.

In operation, the usual spike, or an equivalent bolt has its point inserted into the top of the opening or core-hole and the spike is guided to its seat by the parallel walls of the straight portion, 2, of the opening at the inlet end thereof and as the spike is driven 15 in place, the point of the same will be made to engage the spiral-wall, 3, formed in the central portion of the recess or core-opening; thus the entering part of the spike will be given a progressive partial twist until the 20 driving point of said spike reaches and enters the lower straight portion 21 of the recess or core-hole, when the parallel walls at this part of the recess or hole act to untwist this entering part of the spike or bolt 25 and straighten out the same, as the spike is being finally seated. Thus when the spike is fully seated, the opposite ends of the same will be straight and untwisted while the intermediate portion will be twisted and will 30 remain twisted as long as the spike is in use, and there will be no tendency of the spike to untwist and to be loosened from its seat in the tie, or other part.

Upon withdrawing the spike, which operation may be performed by the usual claw-bar employed by railroads for similar purposes, the twisted intermediate portion of the spike, when drawn upwardly into the straight and untwisted upper portion of the 40 spike recess or core-hole, will be untwisted during its passage therethrough, and while the point or entering end of the spike or bolt will in turn be twisted by being drawn upwardly through the spiral portion of the 45 recess or core-hole, this twist is finally taken out of this part during the passage of the same through the upper and untwisted portion of the recess or opening.

While I have described my improvement 50 in connection with a railway tie and a rail to be secured thereto, I do not limit myself to this particular use of the improvement as other parts may be similarly secured and hence the improvement is to be understood 55 as not being confined to any particular field of industry. As a means for securing a railway rail to a tie, the improvement has decided advantages as the square hole running straight and having parallel walls for 60 a part of its length both top and bottom, keeps the spike from yielding to a tendency to twist out of place. Such an opening or core-hole can readily be made, and the vibration of passing trains will not loosen the 65 spike.

Having thus described my invention what I claim as new and desire to secure by Letters Patent is:—

1. The combination of two parts adapted to be secured one to the other, one of said parts having a recess or hole the opposite end portions of which have parallel walls extending inwardly for a substantial distance, said recess or hole having the walls of the portion intermediate of said end portions of spiral form, and a headed fastening adapted to be driven into said recess or 70 and to be spirally twisted in its passage said spiral wall.

2. The combination of a spike or bolt two parts adapted to be secured thereby to the other, one of said parts having a spike recess or hole whose longitudinal central portion has spirally twisted walls whose terminals merge into end portions of the recess 75 or hole of substantial length and having untwisted walls, said spike or bolt adapted to be twisted in the direction of its length while being forced past the twisted portion of said recess.

3. The combination of two parts adapted to be secured one to the other, one of said parts having a spike or bolt-receiving recess or hole formed in it, said recess or hole having spirally formed opposed walls intermediate of its length and having opposite end portions of substantial length with parallel opposed walls devoid of spiral, and a spike or bolt adapted to be forcibly driven into said recess or hole and to be twisted in the 85 direction of its length by and during its passage between said spirally formed walls.

4. The combination of two parts adapted to be secured one to the other, one of said parts having a spike or bolt-receiving recess or hole through it a portion of whose interior is of spiral form and whose end portion for a substantial distance are devoid of spiral and merge into the spiral portion, and a spike or bolt adapted to be forcibly driven into said recess or hole and to be twisted by its passage through the spirally formed portion of the recess or hole and to be untwisted or straightened by and during its passage through said end portions of 100 said recess or opening.

5. A metallic railway tie having a vertical flange extending longitudinally thereof, said flange being formed integrally with rail seats and interior spike receiving holes at 105 the sides of the seats, each of said holes having straight portions with substantially parallel walls at its opposite ends and having the portion intermediate of said ends formed with spiral walls adapted to twist a spike or bolt when the latter is driven into the hole while in engagement with said spiral walls.

6. A metallic railway tie having a vertical flange extending longitudinally there- 110

- of, said flange being formed integrally with rail seats and interior spike receiving holes at the sides of the seats, each of said holes having straight portions with substantially parallel walls at its opposite ends and having the portion intermediate of said ends formed with spiral walls adapted to twist a spike or bolt when the latter is driven into the hole while in engagement with said spiral walls, said straight end portions of the hole adapted to untwist the spike or bolt while passing therethrough.
7. A metallic railway tie having a rail seat and a spike or bolt hole at the side thereof and extending toward the base of
- the tie, said hole having spiral walls in a portion intermediate of its ends adapted to impart a twist to a spike or bolt forced past the same, and said hole having a portion below the spiral walls with parallel walls 20 devoid of spiral and adapted to untwist the twisted portion of the spike or bolt driven thereinto.
